SYNCHRONIZING APPARATUS

Viktor Aigner, Berlin-Charlottenburg, Germany,
assignor to General Electric Company, a corporation of New York

Application May 12, 1937, Serial No. 142,273
In Germany May 25, 1936

11 Claims. (Cl. 171—118)

My invention relates to improvements in synchronizing apparatus and more particularly to improvements in synchronism indicators and also synchronizing devices for automatically controlling the closing operation of means for connecting two alternating current circuits or systems whereby to start the closing operation at a permissible slip frequency sufficiently prior to synchronism to insure a completion of the connection when their circuit voltages are substantially alike in phase without material shock to the systems.

It has been proposed to control the paralleling or synchronizing connection of two alternating current circuits or systems by a device to which a slip voltage, that is, a voltage dependent on the phase difference between the electro-motive forces of the circuits, is supplied through storage circuits which permit the current effective in the device to attain its minimum value only when the slip frequency, that is, the difference between the frequencies of the electro-motive forces of the circuits, is sufficiently small. One advantageous arrangement for accomplishing this operation embodies a connection in which the rectified slip voltage and also a voltage proportional to its rate of change are supplied to the indicating or control devices in such a way that, when these quantities reach their minimum values, the synchronizing operation is started.

In order to determine the rate of change of the rectified slip voltage, a circuit comprising a rectifier and a condenser is used. In this connection, the function of the condenser is to provide the first derivative with respect to time of the rectified slip voltage or in other words, the rate of change of the rectified slip voltage. With this arrangement, the slip voltage is supplied to a rectifier and condenser and the voltage to be impressed on the device taken from the rectifier. This, however, has the disadvantage that the influence of the normal power system frequency is present in the final result.

In order to avoid such a disadvantage, I provide in accordance with my invention an arrangement for eliminating the normal power system or supply frequency effect from the slip voltage before obtaining its first derivative. This and other objects of my invention will appear in more detail hereinafter.

My invention will be better understood from the following description when considered in connection with the accompanying four sheets of drawings and its scope will be pointed out in the appended claims.

In the drawings, Fig. 1 illustrates diagrammatically a synchronizing arrangement embodying my invention; Figs. 2 and 3 are curve diagrams explanatory of the embodiment of my invention shown in Fig. 1; Fig. 4 illustrates diagrammatically a modification of a part of the embodiment of my invention shown in Fig. 1; Fig. 5 is a curve diagram explanatory of the embodiment of my invention shown in Fig. 4; Fig. 6 illustrates diagrammatically another modification of my invention; Fig. 7 is a curve diagram explanatory of the embodiment of my invention shown in Fig. 6; Fig. 8 illustrates diagrammatically a further embodiment of my invention; Figs. 9 and 10 are curve diagrams explanatory of the embodiment of my invention shown in Fig. 8, and Fig. 11 illustrates diagrammatically a modification of a part of the embodiment of my invention shown in Fig. 8.

In Fig. 1 two polyphase alternating current circuits or systems, represented by phase conductors 15 and 16 respectively, are arranged to be interconnected by suitable switching means illustrated as a latched closed circuit breaker 17. This is shown as having a closing coil 18 whose circuit may include a circuit breaker auxiliary switch 19 which is closed when the circuit breaker is open and vice versa. In order to obtain the voltages desired for the synchronism indication and control of the switch 17, there may be provided potential transformers 20 and 21 which are respectively connected to be energized from corresponding phases of the systems 15 and 16. The secondaries of these transformers are connected in opposition so as to obtain the difference between the electromotive forces of the systems or the slip voltage which is dependent on the phase angle between the electromotive forces. The secondary circuit may include an indicating lamp 14 which will be dark when the systems are in synchronism.

Any suitable synchronism indicating or control means 22, illustrated as having two energizing windings 23 and 24, may be used. This device may comprise two ammeters, each exerting a torque on the same shaft. As shown, the device 22 has a movable indicating or contact controlling member 25 which may be biased to circuit closing position by a spring 26. In some cases it may be advantageous to provide a suitably adjustable stop 27 for the contact member 25 so that it can move from its "in phase" position only a small amount. In this way any stored kinetic energy which might tend to cause

an undesired switching operation is so limited as practically to eliminate such a possibility.

In order to control the device 22 in accordance with my invention, the winding 23 is connected through resistances 28, 29 and 30 and a condenser 31 to a rectifier 32 which is shown full-wave and which is connected in the secondary circuit of the potential transformers 20 and 21 so as to be energized in accordance with the slip voltage E. Consequently the winding 23 is energized in dependence on the rectified slip voltage E_r. As shown in the upper portion of Fig. 2 schematically by section lines the rectified voltage E_r as measured across the resistance 28 contains impulses at power system frequency. These in turn would affect the winding 23 except for the filtering and smoothing action of the condenser 31. The current I_r in the winding 23, therefore, assumes a form such as shown in the lower portion of Fig. 2 opposite a point below the condenser 31. The current I_r in the winding 23 accordingly corresponds directly to the slip voltage.

In accordance with my invention, the winding 24 of the device 22 is connected to be energized in dependence on the rate of change or the first derivative with respect to time of the rectified and filtered slip voltage E_r. For this purpose the winding 24 may be connected in series with a condenser 33 which is energized from the secondary circuit of the potential transformers 20 and 21 through a rectifier 34, shown full-wave, a filtering network comprising condensers 35 and inductances 36, and a loading resistance 37. In this way impulses at power system frequency are eliminated from the rectified slip voltage E_r, shown in the upper portion of Fig. 3, before the rectified and filtered voltage E_r in the form shown in the middle portion of Fig. 3 as measured across the loading resistance 37, for example, is effective on the condenser 33. Consequently, in the current circuit of the condenser 33 and the winding 24, a current I_{rf} flows which is dependent on the first derivative with respect to time of the rectified and filtered slip voltage.

When the sum of the effects exerted by I_r and I_{rf} through the windings 23 and 24 falls below a predetermined value, the control member 25, under the influence of spring 26, closes its contacts 38 in the circuit 39 of the closing coil 18 to energize the coil from a suitable source 40. This effects the closing of the circuit breaker 17 whereby to interconnect the systems 15 and 16 when they are in synchronism. The closing coil circuit 39 may be provided with a control switch 41, which may be normally open, but closable at will when an automatic synchronizing operation is desired. Similarly the secondary alternating current voltage difference circuit of the transformers 20 and 21 may be provided with a control switch 41' which may be normally open but closable at will when an automatic synchronizing operation is desired.

In order that the operation of the device 22 may be dependent on a current of less pulsating value than I_{rf}, the embodiment of my invention, shown in Fig. 1, may be modified as shown in Fig. 4. In this modification, the connection and arrangement of parts above the points 42, 43, 44 and 45 may be just as shown above the correspondingly numbered points in Fig. 1. In circuit with the loading resistance 37, there are connected in series the condenser 33 and a loading resistance 46 whereby to obtain across the resistance 46 a voltage e which is shown in the top

portion of Fig. 5 and which corresponds to the current I_{rf}, shown in the bottom portion of Fig. 3. Across the resistance 46, or a portion thereof, I connect a rectifier 47 which is accordingly energized in dependence on the voltage e or K_e, K representing a constant. From this rectifier, which is shown full wave, the winding 24 of the device 22 is supplied through a loading resistance 48 in a circuit which includes a condenser 49 and may also include series limiting resistances 50 and 51. With this arrangement, the voltage across the resistance 48 corresponds to the voltage e_r, shown in the middle portion of Fig. 5. The condenser 49 is thus charged through the resistance 50. Consequently, the winding 24 is energized by a current i, shown in the bottom portion of Fig. 5. This current is obtained indirectly from the voltage e which is proportional to I_{rf} by rectifying I_{rf} which corresponds to E_r, the first derivative of the rectified slip voltage after filtering. It will be apparent that the variation in magnitude of this current i for a given slip frequency can be kept as small as desired by suitably proportioning the resistances 48, 50 and 51 and the condenser 49.

When the sum of the effects exerted by I_r and i through the windings 23 and 24 falls below a predetermined value, the condition is then satisfied that the slip frequency does not exceed an amount safe for synchronizing and that the phase angle between the voltages of the systems is not too large for safe closing. Under these conditions, the control member 25 closes its contacts 38 whereby to effect the closing of the synchronizing switch 17.

Instead of having a single device responsive to both the slip voltage and the rate of change thereof, my invention may be embodied in separate indicating or synchronizing devices in such a way that the synchronizing operation is dependent on the simultaneous operation of these devices, which operate to permit circuit interconnection, one when the rate of change of the rectified slip voltage is less than a predetermined mean value and another when the rectified slip voltage is less than a predetermined value. In accordance with my invention, the rectifier and filter circuits are so disposed that, at least, in the circuit which supplies the voltage proportional to the rate of change of the rectified slip voltage, the pulsations at power system frequency are eliminated. Thus, as shown in Fig. 6, the device 220, which operates in response to the rate of change of the rectified slip voltage E_r, is supplied through the rectifier 34 which is energized by the slip voltage E. On the direct current side of this rectifier, the voltage indicated as E_r at the top of Fig. 7 is freed of the power system frequency pulsations by the filter network comprising the condensers 35 and the inductances 36 so that the envelope of the rectified slip voltage, indicated as E_{rf} in Fig. 7, appears across the loading resistance 37. This voltage establishes in the condenser 33 a current I_{rf} shown in Fig. 7. This current produces a voltage drop, e, also shown in Fig. 7, across the resistance 46. With the rectifier 47 connected to be energized by this voltage, or a fixed portion K_e thereof, there results the rectified voltage e_r which is shown in Fig. 7 and which appears across the loading resistance 48. This voltage e_r is proportional to the rate of change of the slip voltage. Accordingly, the condenser 49 is charged through the resistance 50. The winding 240 of the device 220 is, therefore, energized from the condenser 49 by a current i

which, with a condenser of sufficient size, can be made practically constant for any given rate of change of slip voltage and which will have a magnitude dependent on this rate of change.

5 The device 220, which may be of ammetric type, accordingly operates to open its contacts 221 whenever the slip frequency decreases to a value at which synchronizing is permissible. For control purposes, the device 220 may be arranged 10 to control an auxiliary relay 52 whose contacts 53 are closed when the relay is deenergized. The relay 52 is, in turn, arranged to cooperate in the control of a circuit breaker closing relay 54 which cannot operate to close its contacts 55 in the circuit 39 of the closing coil while the relay 52 is energized.

In order that the closing operation of the circuit breaker 17 may be dependent on the slip voltage, I provide a device 222 which may be of an alternating current voltmetric type and whose winding 230 may be connected directly to the secondary circuit of the potential transformers 20 and 21 for energization in accordance with the slip voltage without rectification thereof. The 20 movement of the circuit controlling member 251 of the device 222 may, accordingly, be dependent on the momentary value of the slip voltage or more correctly the effective value thereof. It thus shows how the effective value of the power system frequency varies, and this variation corresponds with the slip voltage. Through its contacts 221', the device 222 controls an auxiliary relay 56, which is deenergized when the contacts 221' are open, to close its contacts 57 and thereby 30 to control in cooperation with the device 220, the energization of the closing control relay 54 and the closing of the circuit breaker 17. Instead of having the device 222 of an alternating current type energized in accordance with the slip voltage before rectification, it may be a direct current device with its winding 230 connected across the resistance 37 to be energized in dependence on the rectified and filtered slip voltage E_{rf} , as shown in Fig. 8. 56 when the voltage e is negative. The first arrangement is, however, preferable because beginning at the positive half-wave of e , the full operating current is at once available and, consequently, effects the closing of the contacts of the relay 61 with a powerful impulse and without any delay.

10 The arrangement of the contacts 221', which effects closing of these contacts when equality occurs between a quantity proportional to the rate of change of the slip voltage and a quantity proportional to the momentary value of the slip voltage, can also be obtained electrically instead of mechanically by the embodiment of my invention illustrated in Fig. 11. The part of Fig. 11 above the points 42 and 43 will be understood to be similar to the arrangement shown in Fig. 8 above the points 42 and 43. For this electrical balance I provide, in place of the devices 220' and 222, a device such as a differential relay 63 whose windings 64 and 65 are arranged for opposing effects.

15 If, in the connection of the winding 65 for energization in dependence on E_{rf} , the effect thereof in the decreasing range of the slip cycle, that is, from 180° to 360°, as shown in Fig. 10, is overcome by the effect of the winding 64 which, as shown in Fig. 11, is energized in dependence on i , then the contacts 66 close prior to synchronization 20 at an instant which is determined by the slip frequency dependent advance angle to insure a time dependent on the switch closing time. The conditions will be apparent from Fig. 10 in which the releasing conditions; that is, the points of intersection of er curves with the E_{rf} curve are represented for different angles $\alpha_0, \alpha_1, \alpha_2, \alpha_3$. Thus the contacts 66 close as soon as E_{rf} , which is proportional to the slip voltage, falls below the corresponding values of i which is proportional 25 to er .

25 If the comparison of the two measuring quantities is made with the devices 220' and 222, as in the arrangements illustrated in Figs. 6 and 8, then the device 220' must have a high torque in order 30 that the position of the contacts 221' may not be altered by engaging the controlling member 251. The arrangement may, however, be so arranged that the control member of the device 222 has a high torque and the control member of the device 220' a small torque. In this way the device 222 carries the contacts 221' into the range in which the contacts are to be closed. The interruption occurs as soon as ME_{rf} is less than NE_r , M and N being constants. In order to insure a positive 35 contacting action, the natural frequency of the device 220' should be greater than that of the device 222.

35 As shown in Fig. 11, the winding 64 of the device 63 is connected to be energized in the same way as the winding 240' of the device 220' shown in Figs. 6 and 8. This, however, brings in the delayed or retarding action involved in the discharging and charging of the condenser 49. This delayed action might result in the deviation 40 of the movement of the device 220' from the desired movement corresponding to the momentary slip frequency. To avoid this, the winding 240' of the device 220' and similarly, the winding 64 of the device 63 may be connected directly 45 across the loading resistance 48. In this case, a current proportional to E_{rf} flows in the winding 230 of the device 222 of Fig. 8 and, similarly, in the winding 65 of the device 63 of Fig. 11, and the winding 240' of the device 220' of Fig. 8 or 50 the winding 64 of the device 63 of Fig. 11 is ener-

5 gized by a current proportional to er . If the slip frequency is zero, then the relay 56 of Figs. 6 and 8 is deenergized to close its contacts or the contacts of the device 63 close at α_0 of Fig. 10 since the rate of change of slip voltage equals zero. With finite slip frequency, the advance angle increases with the slip frequency since, as appears from Fig. 10, a point of intersection of the er curve and the E_{rf} curve will occur earlier when the slip frequency is higher. Moreover the device 61 10 shown in Fig. 8 prevents a synchronizing connection during the rising half of the slip cycle curve.

15 The winding 64 of the device 63 of Fig. 11 may be connected across the resistance 46 or a part thereof so that during the slip cycle range of zero to 180°, the winding 64 is energized to assist the winding 65 whereby, within this range, no closing of the contacts 66 can occur. Thus even though the slip frequency is below the permissible value and the contacts 221' of the device 220 open to drop out the relay 52, the circuit of the closing relay 54 will be open at the contacts 66. In the slip cycle range 180°-360°, the contacts 66 close at an angle whose value is proportional 20 to the slip frequency. The winding 240' of the device 220' may be connected for energization as is the device 61 of Fig. 8. When so connected, the device 220' will effect the closing of the contacts 221' in the slip cycle range 0° to 180°, that is, the contacts 221' are caused to move to engage the control member 251. With this connection of the winding 240', the rectifier 60 would cut off the negative half-waves of e from the winding 240' as the electromotive forces depart 25 from the in-phase position. Then, since the zero, or rest position, of the contacts 221' does not permit a closing of these contacts unless the control member 251 is also in the zero, or rest position, the device 61 is not necessary.

30 Depending upon the direction of approach to synchronization, that is, as to whether the decreasing slip direction is directed to the right or left in Fig. 10, the winding 64 of the relay 63 or the winding 240' of the device 220' and the rectifier 40 60 in circuit therewith would have to have their relative polarity reversed by a frequency comparison relay.

35 The current flowing in the device 220 can be used as a measure for the required adjustment of the prime mover of the machine to be synchronized. Since the movement of the control member of the device 220 is limited by the contact 221, the slip frequency can be determined from a second ammetric device 68, shown in Fig. 8, whose 45 winding 69 is connected in series with the winding of the device 220 and which has a movable member 70 whose angular movement is not limited. By means of a frequency comparison relay, examples of which are well known to the 50 art, it can readily be determined whether the approach to synchronization is in one direction or the other.

45 While I have shown and described my invention in considerable detail, I do not desire to be 55 limited to the exact arrangements shown, but seek to cover in the appended claims all those modifications that fall within the true spirit and scope of my invention.

50 What I claim as new and desire to secure by 70 Letters Patent of the United States is:

55 1. In combination, two alternating current electric systems, means for connecting said systems, and means for controlling the operation of said connecting means including means for deriv- 75

ing a voltage dependent on the slip voltage of the systems, means for obtaining from said slip voltage a practically constant continuous current whose magnitude is dependent on the slip frequency of the systems, and means connected to be energized responsively to said slip voltage and said current for controlling the operation of said connecting means in dependence on the simultaneous values of said voltage and current.

5 2. In combination, two alternating current electric systems, means for connecting said systems, and means for controlling the operation of said connecting means including means for deriving a voltage dependent on the slip voltage of the systems, means for obtaining from said slip voltage a practically constant continuous current whose magnitude is dependent on the slip frequency of the systems, and means connected to be energized responsively to the sum of an effect 10 dependent on the slip voltage and an effect dependent on said current.

15 3. In combination, two alternating current electric systems, means for connecting said systems, and means for controlling the operation of said connecting means including means for deriving a voltage dependent on the slip voltage of the system, means for obtaining from said slip voltage a practically constant continuous current whose magnitude is dependent on the slip frequency of the systems, means connected to be energized responsively to said slip voltage and means connected to be energized responsively to said current, said voltage and current energized means jointly controlling the operation of said connecting 20 means.

25 4. In combination, two alternating current electric systems, means for connecting said systems, and means for controlling the operation of said connecting means including means for deriving a voltage dependent on the slip voltage of the systems, means for obtaining from said slip voltage a practically constant continuous current whose magnitude is dependent on the slip frequency of the systems, means connected to be energized responsively to said current, means connected to be energized responsively to said slip voltage and means responsive to said current for controlling the means responsive to said slip voltage, and means jointly responsive to said current energized means and said slip voltage energized means for controlling the operation of said connecting means.

30 5. In combination, two alternating current electric systems, means for connecting said systems, and means for controlling the operation of said connecting means including means for deriving a voltage dependent on the slip voltage of the systems, means for obtaining from said slip voltage a practically constant continuous current whose magnitude is dependent on the slip frequency of the systems, and means connected to be energized responsively to said current, means connected to be energized responsively to said slip voltage, means for controlling the advance angle of said slip voltage energized means and means jointly controlled by said current energized means, said slip voltage energized means and said advance angle control means for controlling the operation of said connecting means.

35 6. In combination, two alternating current electric systems, means for connecting said systems, and means for controlling the operation of said connecting means including means for deriving a voltage dependent on the slip voltage of the sys-

tems, means for obtaining from said slip voltage a practically constant continuous current whose magnitude is dependent on the slip frequency of the system, means connected to be energized responsively to said current, means to be connected to be energized responsively to said slip voltage, means for controlling the advance angle of said slip voltage energized means, means jointly controlled by said current energized means, said slip voltage energized means and said advance angle control means for controlling the operation of said connecting means and means for eliminating the control effect of said slip voltage energized means during a predetermined portion of the slip cycle.

40 7. In combination, two alternating current electric systems, means for connecting said systems, and means for controlling the operation of said connecting means including means for deriving a voltage dependent on the slip voltage of said systems, means for deriving a voltage dependent on the rate of change of said slip voltage, cooperating means connected to be energized respectively in response to said slip voltage and said rate of change voltage, means connected to be energized 25 in dependence on said rate of change voltage, and means jointly controlled by said cooperating slip voltage and rate of change voltage responsive means and said rate of change voltage dependent energized means for controlling said connecting 30 means.

45 8. In combination, two alternating current electric systems, means for connecting said systems, and means for controlling the operation of said connecting means including means for deriving a voltage dependent on the slip voltage of the systems, means for deriving a voltage dependent on the rate of change of said slip voltage, means connected to be energized responsively to said slip voltage, means connected to be energized in dependence on only said rate of change voltage, control means connected to be energized in dependence on said rate of change voltage for controlling said slip voltage energized means, and means jointly responsive to said rate of change 45 voltage dependent energized means, said slip voltage responsive means and said last mentioned control means.

50 9. In combination, two alternating current electric systems, means for connecting said systems, and means for controlling the operation of said connecting means including means for deriving a voltage dependent on the slip voltage of said systems and means for deriving a voltage dependent on the rate of change of said slip voltage, means connected to be energized responsively to said slip voltage, means connected to be energized in dependence on said rate of change voltage, control means connected to be energized in dependence on said rate of change voltage for controlling said slip voltage energized means, means jointly responsive to said rate of change voltage dependent energized means, said slip voltage responsive means and said last mentioned control means, and means for eliminating the control effect of said slip voltage energized means during a predetermined portion of the slip cycle.

55 10. In combination, two alternating current electric systems and synchronizing means therefore, comprising means for deriving a voltage dependent on the slip voltage of the systems and means for obtaining from said slip voltage a practically constant continuous current whose magnitude is dependent on the slip frequency of the systems.

11. In combination, two alternating current electric systems, means for connecting said systems, and means for controlling the operation of said connecting means including means for deriving a voltage dependent on the slip voltage of the systems, means for rectifying said derived voltage, means for subsequently filtering the power system frequency from said rectified voltage, means for obtaining from said rectified and

filtered voltage a current dependent on the rate-of-change of said slip voltage, and a device having two cooperating windings respectively connected to be energized responsively to said current and to a current proportional to said slip voltage for controlling the operation of said connecting means in dependence on the simultaneous values of said slip and rate-of-change voltages.

VIKTOR AIGNER.
